UNITED STATES PATENT OFFICE

2,641,224

AUXILIARY FLOOR FOR POULTRY HOUSES

Walter T. Seidel and Robert A. Seidel,
Baltimore, Md.

Application November 22, 1950, Serial No. 197,124

1 Claim. (Cl. 119—21)

1

This invention relates to fabricated wire floors for poultry houses.

An object of the invention is the provision of an elevated floor for poultry houses in which the floor is formed of fabricated wire to support the poultry above the main floor to permit droppings to pass through the fabricated floor thereby providing better sanitary conditions for the poultry, the elevated floor being readily removable to permit cleaning of both the main floor of the poultry house and the fabricated floor, the last-mentioned floor being built in sections to facilitate the application or removal of said floor.

Another object of the invention is the provision of an elevated auxiliary wire-fabric floor for poultry houses in which the supporting legs are removable for flat application of the legs to the floor for shipping purposes, said legs being so constructed that they may be assembled readily in vertical positions for not only supporting the poultry, but supporting a caretaker while permitting droppings to pass through the auxiliary floor.

A further object of the invention is the provision of an elevated fabricated wire screen floor for supporting poultry above the droppings on the main floor of a poultry house to create better sanitary conditions therein, said floor being raised above the floor of the poultry house by fabricated wire legs or supports which may be moved to inoperative positions to facilitate packing of the floor in a compact bundle for shipping purposes, but which may be restored readily as a rigid elevating means for the fabricated floor by simple operations before the fabricated floor is applied to the main floor of the house.

This invention is best understood from a consideration of the following detailed description in connection with the accompanying drawings forming part of the specification, nevertheless, it must be borne in mind that the invention is not confined to the disclosure, but is susceptible of such changes and modifications as shall define no material departure from the salient features of the invention as expressed in the appended claim.

In the drawings:

Figure 1 is a fragmentary plan view of an elevated wire floor section for use in poultry houses.

Figure 2 is a transverse vertical section of the floor taken along the line 2—2 of Figure 1.

Figure 3 is an enlarged fragmentary bottom view with parts broken away in perspective of the supporting structure for the fabricated auxiliary floor.

2

Figure 4 is a greatly enlarged fragmentary vertical section of the floor showing the method of folding the supporting legs of the elevated floor upon said floor when shipped.

Figure 5 is an enlarged longitudinal side elevational view with parts broken away of the intersecting supports removed from the fabricated wire floor before the floors are shipped, and

Figure 6 is a plan view on a reduced scale of a large area of flooring made up of a plurality of the floor sections shown in Figure 1.

Referring more particularly to Figures 1 and 6 of the drawings, it will be noted that the fabricated wire-sections 10 or 10a of an auxiliary floor 11 may be composed of any number of squares 12 depending upon the area and shape of the main floor of a poultry house. Where large areas must be covered, a number of the sections may be employed and secured together in a simple manner. The fabricated wire floor is elevated above the main floor by supports which will be described presently.

The auxiliary floor of each section consists of a suitable length of a fabricated wire screen having a predetermined width. The screen is formed of longitudinal and right angularly disposed transverse wires 13 and 14 respectively, the contacting portions of the two sets of wires being spot-welded to provide the necessary strength to support the weight of an attendant. The mesh of the screen is such that the droppings will pass readily through the screen and be deposited on the main floor of the poultry house so that the poultry will have a relatively clean floor to walk on. The ends of the wires at the outer edges of the auxiliary floor 11 are spot-welded to points on the rods 15 and 16 of a rectangular frame 17 (Figure 1) formed of a heavy wire.

The frame and the attached auxiliary floor are elevated above the main floor of the poultry house by a pair of supporting side legs 20 and by a pair of end supports or legs 21. The supports 20 include vertical brace rods 22 which have one end spot welded to a bottom rod 23 which is adapted to rest on the main floor. The other ends of the rods 22 are provided with eyes 24 which are received by the rods 15. The legs 21 include a bottom rod 25 and brace rods 26 which have one end each welded to said bar, while the other ends of said rods are equipped with eyes 26a receiving the associated rod 16 of the frame 17. It will be noted that one end of each of the respective bottom rods 23 and 25 is provided with a hook 27 or 28 for a purpose which will be ex-

plained presently. The other ends of the rods 23 and 25 as shown in Figure 3 are welded to the ends of the alined brace rods.

The centers of the sections of the auxiliary floor 11 are reinforced by a pair of longitudinal supports 30 and 31 disposed at right angles to each other. These supports cross each other in such a manner that each square foot of surface of the auxiliary floor is braced or reinforced. Thus, it will be seen that in an auxiliary floor containing four square feet, two supports 30 and 31 will be employed while in a floor containing nine square feet four longer supports will be required. In this case, the two supports 31 will have two pairs of inbent portions 37.

Referring more particularly to Figures 2, 3 and 5, the support 30 consists of a pair of parallel horizontal rods 32 which are joined together by parallel vertical brace rods 33 and 33a welded at the ends thereof at spaced points on the parallel rods 32. The intermediate vertical rod 33a is in contact with an intermediate vertical rod 34a of the support 31 which has other spaced vertical rods 34 parallel to the rod 34a. The ends of the rods 34 are welded to the straight portions of parallel horizontal rods 25 and 36 of the support 31. The ends of the vertical rods 34a has its ends welded to opposed inbent portions 37 of the rods 35 and 26. These inbent portions 37 receive the rods 32 of the support 30 to provide a neat fit. A wire 39 has a free end welded at 40 to the rod 34a and is adapted to be wrapped around both contacting rods 33a and 34a to retain the centers of the supports 30 and 31 in position when the auxiliary floor is placed upon the main floor of the poultry house.

The opposite ends of the horizontal rods 32 of the support 30 are provided with hooks 41 which are adapted to receive the middle rods 26 of the pair of supports 21. The opposite ends of the horizontal rods 35 and 36 are provided likewise with hooks 42 at the opposite ends thereof to receive the intermediate vertical rods 22 of the supports 20.

All of the hooks remain open including the hooks 27 and 28 so that the supports may be removed when the floors are packed for shipment. The removal of the supports 30 and 31 and the hooks 27 and 28 releases the pairs of supports 20 and 21 so that the last-mentioned supports may be rocked to an inoperative position upon the fabricated floor 11 as indicated in dotted lines in Figure 4. The construction of the eyes 24 and 26a and the position of the supports 20 and 21 are such that the supports may be placed in flat contact with the auxiliary floor 11 and the freed supports 30 and 31 are laid upon the first-mentioned folded supports thereby providing a neat package for shipment.

When the auxiliary floors are received by the poultryman, said package of floors are reassembled. The supports 20 and 21 are moved to the vertical positions shown in Figures 3 and 4. The hooks 41 on the ends of the rods 32 of the support 30 are applied to the rods 26 of the supports 21. The support 31 is inserted horizontally through the center of the support 30 and then turned to a vertical position whence the hooks 42 on the ends of the rods 35 and 36 are applied to the rods 22 of the opposed parallel supports

20. The wire 39 is wrapped around both intermediate rods 33a and 34a.

The hook 27 on an end of each of the rods 23 and hook 28 on an end of each of the rods 45 are applied respectively to the lower ends of the outer rods 26 and 22 only. It will be noted that each rod 25 has one end provided with a hook 28 while the other end is welded to a rod 26. Likewise, each rod 23 has one end welded to an outer vertical rod 22 while the other end is provided with a hook 27. The hooks 27 are disposed diagonally in each square section of the auxiliary floor. The hooks 28 are similarly disposed in each section. This arrangement provides a knock-down construction and permits the supports 20 and 21 to be folded on the screen before the auxiliary floors are shipped from the factory. When all of the hooks 27 and 28 have been applied to the associated end or outer rods 26 and 22 of the respective supports 21 and 20, the free ends of the hooks are pressed or clamped into position to form eyes so that said supports are fixed in place. The hooks 41 on the ends of the rods 32 and the hooks 42 on the rods 35 and 36 are transformed similarly into eyes for binding the supports 30 and 31 in fixed positions.

All of the rods and the frame 17 forming the various supports for the auxiliary floor 11 are manufactured from relatively heavy wire strands, so that the floor will support a load of at least two hundred pounds. The diameters of the rods of the supports and the wire strands of the frame 11 are substantially the same.

The supports 30 and 31 are intersecting wire frames, and the pairs of supports 20 and 21 are in effect wire frames which are mounted swingably on the frame 17 but become fixed supports when set in position in the poultry house.

What we claim:

40. An auxiliary floor of the knock-down type for poultry houses comprising a rectangular frame, a fabricated wire screen having the edges thereof secured to corresponding sides of the frame by welding, a wire frame swingably mounted on 45 each side of the rectangular frame and forming supports for elevating the screen above the floor of a poultry house, each swingable frame including spaced vertical brace rods and a horizontal rod forming the bottom of a swingable 50 frame, the vertical rods having the lower ends secured to the horizontal rod and the upper ends hinged to a side of the rectangular frame, a hook on one end of each horizontal rod of a swingable frame, the hooks on said frame receiving the vertical rods at the end of the swingable frames forming right angles with each other, and intersecting wire frames providing central supports for the fabricated wire screen, and equipped with hooks receiving intermediate 55 vertical rods on the swingably mounted frames.

WALTER T. SEIDEL.
